DOOR HANGER

Filed April 9, 1936

By *George Heidman*, Attorney

UNITED STATES PATENT OFFICE

2,079,028

DOOR HANGER

Joseph Nemec, Western Springs, Ill.

Application April 9, 1936, Serial No. 73,483

7 Claims. (Cl. 16—105)

My invention relates more particularly to hangers for the conventional baggage car doors or doors of mail and combination club doors and particularly of the sliding type; the invention having for its object the provision of a construction whereby minute adjustments may be made and such adjustments be practically permanent-
ly maintained, while the maintenance cost—due to proper register with the door opening—will be materially reduced.

The invention has for its object the provision of a hanger of comparatively simple construction which may be easily applied and readily adjusted to bring the door into complete register with the door-opening and thus provide a substantially weather-proof closure without resort to im-
proper pressure and hence undue strains.

The objects and advantages of my invention will all be readily comprehended from the de-
tailed description of the accompanying drawing
wherein:

Figure 1 illustrates a pair of my improved hangers, in front elevation, shown applied to a door and top rail of which merely portions are shown.

Figure 2 is a side view of my improved hanger.

Figure 3 is a vertical sectional view taken substantially on the line 3—3 of Figure 1.

Figure 4 is a cross sectional view taken on the line 4—4 of Figure 1.

The specific embodiment of the invention as disclosed in the drawing comprises a roller car-
rying and rail lapping member or casting 10 of proper width and length to extend from the top or supporting rail 11, which is suitably secured to the car wall or side immediately above the door opening and toward one side thereof in the usual manner; the cross-sectional configuration of the rail being shown in Figure 3. One leg or side of the channel rail 11 constitutes a trackway for the roller 12 which is journaled on the pintle or pin 13 which is removably secured in place.

The upper end of the casting or member 10 is of width greater than the diameter of the roller 12 and is of chambered rectangular cross-section as shown at 14 in Figure 4; the upper end of the casting 10 constituting a housing for the flanged roller 12, open at top and bottom.

The rear wall of the housing 14 is apertured to receive the non-threaded end of the pintle or pin 13; while the front wall is made of increased thickness or provided with a boss and this boss portion provided with a tapped opening to receive the enlarged threaded end 15 of the pintle 13. The end 16 of the pintle 13 beyond the

threaded portion 15 is shown rectangular in cross-section so as to fit into a correspondingly shaped slot or opening in a pintle holding plate or locking member 17.

The ends of the plate or locking member 17 are each provided with a tapped hole adapted to be brought into register with tapped holes ar-
ranged in the front wall of the casting or mem-
ber 10 on opposite sides of the pintle receiving
hole. After the pintle 13 is inserted through the
hole in the front wall and through the hub or
hole in the roller, plate or locking member 17
may be applied to the rectangular or non-circu-
lar end 16 of the pintle and the plate used in
firmly screwing the threaded portion of the pin-
tple 13 into the tapped boss portion of the front
wall of the casting 10 and after the pintle is
entirely screwed into place with its inner end
in the hole in the rear wall, the pintle with
locking plate 17 is turned to a point where the
tapped holes in the plate 17 will register with
the tapped holes in the front wall of the cast-
ing 10; the plate being then secured in this ad-
justed position by inserting screws 18, 18 through
the plate 17.

With plate or locking member 17 secured in proper place by screws 18, 18, it is apparent that rotative or unscrewing movement of the pintle, due to the rolling action of roller 12 will be impossible, although a dismantling of the roller carrying element may be readily accomplished if occasion should require.

The forward or outer face of the casting 10, intermediate of the top and the bottom, is formed with an outwardly disposed boss 19 provided with a tapped opening to receive the threaded end of the bolt 20 which passes through the eye of the eye-bolt or adjusting screw 21.

The lower end of the casting 10, at a slight distance beneath the boss 19, is provided with a vertically disposed slot 22 of predetermined length and arranged in alignment with the boss 19, as shown in Figure 1.

To the rear of the skirt or slotted lower portion of casting 10 is a door engaging plate or anchor member 23, which is adapted to be se-
cured to the door 24 in any suitable manner as by screws 25 see Figure 3. The forward face of the anchor member 23 is provided with a ver-
tically elongated boss 26 which is adapted to slide-
ly fit into the slot 22 in the casting or roller carrying member 10; and this boss 26 in turn is provided with an outwardly extending lug 27.

The lug 27 is intended to extend outwardly a

distance sufficient to bring the vertical opening through the lug into vertical alignment with the pivot screw 20 and therefore into position to receive the depending eye-bolt or screw 21, see 5 Figure 3.

The threaded portion of eye-bolt 21 is provided with adjusting nuts 28, 28; one of the nuts being threaded onto the bolt before the latter is inserted through the hole in the lug 27 of the 10 anchor member or plate 23, while the lower nut 28 is then screwed onto the bolt 21 and this nut preferably locked in its adjusted position in any suitable manner as by means of a lock-nut 29.

As shown in Figures 1 and 3, the vertically 15 elongated boss portion 26 of the door anchor member 23 is of length considerably less than the length of the slot 22 in the roller carrying plate or casting 10, thus permitting relative adjusting movement between door anchor 23 and 20 the roller carrying plate 10.

Where the door hanger is used for the large 25 sliding doors of a baggage car, it is usual to employ at least a pair of hangers, as shown in Figure 1, adjacent opposite ends of the door; and if desired the rear lower part of the casting 10 30 may be provided with a pair of vertically disposed serrated ribs or flanges, as at 30, arranged on opposite sides of the door anchor receiving slot 22 in the casting 10; the serrations being adapted 35 to effect slight frictional relation with the face of the door 24 and thus somewhat assist the door anchor 23 in holding the door.

The application of my improved hanger and 40 the mounting of the door on an overhead rail may be readily accomplished by assembling the roller as heretofore described and locking the pintle 13 against accidental movement induced by the repeated back and forth rolling of the rollers along rail 11; then apply the roller carrying element to the overhead rail 11. The anchor members or plates 23 are then vertically 45 secured to the door so as to register with the slot 22 in each roller carrying member or casting 10 and the lug 27 disposed through the slot 22.

The eye-bolt 21, with the upper nut 28 screwed 50 thereon, is then inserted through the hole in the lug 27 and bolt 20 passed through the eye of the bolt and screwed into the tapped hole in the enlarged or boss portion 19 of the roller carrying plate or casting 10. With the bolt 20 in place, the lower nut 28 is then screwed onto the end of 55 the door suspending bolt or member 21 until it engages the lower face of the lug 27. After the lower nut 28 has been screwed lengthwise of the door suspending bolt 21 until the door has been 60 raised from the floor and at the same time will freely fit the door opening, lock-nut 29 is then applied to the bolt 21 and the upper nut 28 screwed downwardly into firm contact with the top of the lug 27.

Member 10 is shown provided with vertically 65 elongated slots 31, on opposite sides of slots 22, adapted to loosely receive bolts with washers as at 32; the bolts being secured to the door. This permits vertical adjustment between door and member 10 to be made while assisting the boss 26 against lateral movement.

With the elongated boss 26 of anchor member 70 23 slidably fitting into the slot 22 in the roller or bearing carrying member, it is evident that lateral or sidewise movement between the door and the hanger member 10 will be impossible and a positive relation between the door and roller carrying member 10 maintained.

As is apparent from the construction illus-

trated, the door is entirely suspended from the bolt 21 and practically micrometer or very fine 5 adjustments can be made. With the conventional door hangers adjustments of a coarser nature, as for example about one-eighth of an inch, are merely possible; whereas with my improved construction adjustments of one-thousandth of an inch are possible and these adjustments made practically permanent, which is not the case with the conventional hangers due 10 to slippage of the ratchets, permitting the door to get out of adjustment and at times making it impossible to operate.

The eye portion of the door suspending bolt 21 15 is preferably provided with flat faces so the bolt 21 may be free to swing on the bolt 20; and instead of the plain roller 12 it is apparent that a roller-bearing type may be employed; and while I believe the construction shown to be the best embodiment of my invention certain modifications 20 may be made without departing from the spirit of my invention which has been described in terms employed merely as terms of description.

What I claim is:

1. A door hanger of the character described 25 comprising a roller carrying member provided at its upper end with a vertically arranged roller while the lower end has a vertically disposed slot; a door supporting element secured to said member; a door anchor adapted to be pendently 30 secured to a door rearward of said member and having a portion extending into the slot of said roller carrying member, said anchor having vertical 35 slideable operative relation with said element; and means whereby an operative adjustable relation between the anchor and said element is provided.

2. A door hanger of the character described 40 comprising a roller carrying member provided with a depending threaded portion and with a vertically disposed slot rearward of the threaded portion; an anchor member adapted to be secured to the door and provided with a portion 45 adapted to slide lengthwise of the slot and having an apertured portion for passage of said depending threaded portion therethrough; and means adjustable on the threaded portion for suspending the anchor member on said depending threaded portion.

3. A door hanger of the character described 50 comprising a roller carrying member; a door supporting element pendently secured at its upper end to the forward face of said member; an anchor member adapted to be secured to the door and having an interengaging sliding relation with the roller carrying member so as to permit vertical 55 adjustment between the two members while preventing lateral movement, said anchor member having a forwardly presented portion adapted to slidably receive said element; and means adjustable lengthwise of the supporting element whereby the relation between said element and the anchor member may be regulated.

4. A door hanger of the character described 60 comprising a member adapted to be slidably suspended from an overhead rail, said member being provided with a vertical slot and with a vertically 65 extending threaded portion disposed forward of the slot; an anchor member adapted to be secured to a door and having a portion disposed through the vertical slot in said first member, said portion being apertured for passage of the threaded portion therethrough; and means 70 adapted to screw lengthwise of the threaded portion and beneath the anchor apertured portion 75

whereby the door is suspended from the threaded portion and its position regulated.

5. A door hanger comprising a bearing carrying member adapted to be slidably suspended from a rail, the lower part of the member being provided with a vertically disposed slot; a threaded pin secured to the forward face of the member above the slot so as to depend forward of the slot; a member adapted to be secured to a door and to slidably fit into said slot, said member having a forwardly disposed apertured lug adapted for free passage of the threaded pin therethrough; and means adapted to screw lengthwise of the pin and beneath said lug whereby the door is held in adjustable suspended position.

6. A door hanger of the character described comprising an elongated member whose upper end is formed to provide a roller receiving pocket open at top and bottom, while the lower end of the member is provided with a vertically disposed slot; a removable pintle adapted to have bearing in the front and rear walls of the pocket; a roller mounted on said pintle so as to extend through the open bottom of said pocket; a threaded pin removably secured to the forward face of the member above the slot so as to depend vertically forward of said slot; an anchor member adapted to be secured to a door and provided with a forwardly disposed portion adapted to be slidable in said slot to prevent independent lateral movement between the anchor and the first mentioned

member, a part of said portion being vertically apertured and disposed beyond the forward face of the elongated member; and means adapted to screw lengthwise of the threaded pin in engagement with said apertured part of the anchor member whereby the door is adjustably suspended from said pin.

7. A door hanger of the character described comprising an elongated plate provided at top with a roller housing portion open at bottom to permit the roller to ride on a rail; the lower end of the plate having vertical slots while the rear face of the plate intermediate of the slots is provided with door engaging serrations; a roller removably mounted in said portion; a threaded pin removably secured at its upper end to said housing member so as to extend vertically in front of one of the slots in the plate; an anchor member adapted to be secured to the upper end of a door and provided with a forwardly disposed elongated lug adapted to slide in one of said slots to prevent independent lateral movement between the two members, said lug having a vertically apertured portion adapted to permit said pin to pass therethrough; door fastening means slidable in the other slots of said plate; and means adapted to screw lengthwise of the threaded pin in engagement with said apertured portion of the lug of the anchor member whereby the door is suspended from said pin and vertical adjustment of the door permitted.

JOSEPH NEMEC.

CERTIFICATE OF CORRECTION.

Patent No. 2,079,028.

May 4, 1937.

JOSEPH NEMEC.

It is hereby certified that error appears in the printed specification of the above numbered patent requiring correction as follows: Page 2, second column, line 30, claim 1, strike out the word "pendently" and insert the same after "element" in line 29; and that the said Letters Patent should be read with this correction therein that the same may conform to the record of the case in the Patent Office.

Signed and sealed this 29th day of June, A. D. 1937.
